DESIGN FOR A DICTATING MACHINE MOTOR

Robert L. Stone, Guilford, Conn., assignor to The
SoundScriber Corporation, New Haven, Conn.,
a corporation of Connecticut

Application July 5, 1947, Serial No. 140,105

Term of patent 14 years

(Cl. D26—5)

To all whom it may concern:

Be it known that I, Robert L. Stone, a citizen of the United States, residing in Guilford, county of New Haven, and State of Connecticut, have invented a new, original, and ornamental Design for a Dictating Machine Motor, of which the following is a specification, reference being had to the accompanying drawing, forming a part thereof.

Fig. 1 is a rear view of the dictating machine motor showing my new design.

Fig. 2 is a side view of the same.

Fig. 3 is a front view of the same.

Fig. 4 is a top view of the same.

Fig. 5 is a side view of the same taken 180 degrees from Fig. 2.

Fig. 6 is a bottom view of the same.

I claim:

The ornamental design for a dictating machine motor, as shown.

ROBERT L. STONE.
